UNITED STATES PATENT OFFICE.

HENRY C. HODGES AND CHARLES H. PARSHALL, OF DETROIT, MICHIGAN.

LUBRICATOR.

SPECIFICATION forming part of Letters Patent No. 225,985, dated March 30, 1880.

Application filed January 31, 1880.

To all whom it may concern:

Be it known that we, HENRY C. HODGES and CHARLES H. PARSHALL, of Detroit, county of Wayne, State of Michigan, have invented a new and useful Improvement in Lubricators; and we hereby declare the following to be a full, clear, and exact description of the same, such as will enable others skilled in the art to which it pertains to make and use it, reference being had to the accompanying drawings, which form a part of this specification.

Our invention relates to lubricators for steam-boilers, and more particularly to that class of lubricators where steam-pressure is exerted within the body of the lubricator.

The object of our invention is to overcome the undue waste of oil at the moment of shutting off the steam, and it is accomplished by providing a valve located in the oil-exit passage, which shall open automatically by the pressure of steam back through that passage when steam is turned on, and shall close automatically by the pressure of steam through another passage, or by other external pressure, upon the same valve when the steam is shut off from the cylinder.

In the drawings, Figure 1 is a view of a lubricator with our improvement attached and shown in section. In this figure the device is represented as attached to the top of the boiler, with pipes D and D' independent. Fig. 2 is a variation, representing the device attached to the end of the boiler and the pipe D' leading from the steam-pipe; Fig. 3, a separate view of the valve-chamber. Figs. 4 and 5 are variations of the invention.

Heretofore in that class of lubricators where in an equilibrium of steam-pressure, when in use, is maintained within the lubricator a difficulty has been experienced, owing to the rapid escape of oil at the moment steam is shut off from the parts that are being lubricated.

Where the steam-pipe and oil-outlet both led from the dry-pipe or other steam source this difficulty was doubtless due to the fact that when steam is shut off from the dry-pipe a quantity of vapor under pressure is housed within the lubricator, and forces the oil out in coming to an equilibrium with the medium in the dry-pipe; but where the steam-pipe leads

from the boiler and the oil-exit discharge into the dry-pipe the wastage is caused by the fact that when steam is cut off from the dry-pipe the preponderance of steam-pressure through 55 the steam-pipe drives the oil out. We propose to overcome this difficulty by providing a valve, as above stated.

A is an ordinary lubricator of any suitable construction. B is its oil-exit passage. 60

C is a transparent water-chamber, through which the oil passes on its way to the parts to be lubricated.

D is a steam-pipe communicating with the steam-space of the boiler E. This device in 65 the drawings is presented as being attached to a locomotive-boiler. Its dry-pipe is represented at F.

In the arrangement shown the oil-exit pipe discharges into the dry-pipe and the steam-pipe D communicates directly with the steam-spaces of the boiler. 70

G is a valve located at any desired point on the oil-exit passage between the oil-reservoir and the oil-discharge point. 75

The valve G has a stem, G', which projects into a small cylinder, H, where it is constantly acted upon by the steam-pressure, the area of the valve G being considerably greater than that of the piston or stem G'. 80

The operation of the device is as follows: When there is steam-pressure in the boiler and the engine is at rest there is a corresponding though somewhat less pressure in the lubricator through the steam-pipe D, and as there 85 is no resisting pressure from the dry-pipe through the oil-exit passage B the steam acting against the stem or piston G' forces the valve G firmly upon its seat and holds it there. Now, when the throttle-valve is opened, so as 90 to admit steam into the dry-pipe, the pressure back through the oil-exit passage B, acting upon the large area of the valve G, will overcome the greater pressure of steam on the valve stem or piston G' in the cylinder or chamber 95 H, and causes the valve to open instantly and remain open until the steam is again shut off from the dry-pipe, at which moment the preponderance of pressure on the stem G' will cause the valve to close quickly and shut off 100 all escape of oil. This alternate operation of opening and closing the valve will take place

automatically as often as the steam is turned on or off from the dry-pipe or engine.

The steam-pipe in Fig. 2 is represented as descending from the top of the lubricator and 5 entering the boiler below the level of the cylinder or chamber H. This construction is designed to prevent accumulation of condense- water in the cylinder or chamber H.

We do not limit ourselves to the employ- 10 ment of a device in which the valve G and plunger G' are in a single piece, for it is appar- ent that the valve may be connected with one end of a pivoted lever and the plunger or a weight or spring at the other end of the pivoted 15 lever. So, also, instead of taking the steam from the steam-pipe D to actuate the valve, there may be an entirely independent steam-passage, D', as shown in Fig. 1, for this particular purpose, and this would be necessary in many con- 20 structions—as, for instance, those in which the steam-pipe D and oil-exit pipe B are both made to take their steam from or open into the dry- pipe, our invention contemplating broadly any 25 construction in which a valve is so arranged in the oil-exit passage as to open by the back pressure of steam through the oil-passage when steam is turned on and close by a preponder- 30 ance of reacting pressure in the opposite direction by an external force or through an op- posing steam-passage when the steam is shut off.

Any form of valve or cock may be employed and the mechanism be changed to adapt it to operate any such valve or cock; but the plun- 35 ger-valve is believed to be best adapted for the purpose, and is consequently the kind of valve shown in the drawings.

In the case illustrated the valve is located between the oil-reservoir and the transparent 40 cylinder or "sight-feed," as it is termed, be- cause this avoids the possibility of the oil enter- 45 ing the transparent chamber.

In Fig. 4 is illustrated a variation of our invention, in which a spring is made to take the 45 place of the reacting steam-pressure, so that the valve will open by the pressure back through the oil-exit passage and close by the pressure of the spring when steam is closed off.

Those parts of the case which are marked 50 with the letter x are all constructed in a single casting, thus avoiding entirely the use of joints in forming these several parts; and this feature is of considerable value in cheapening the construction and avoiding the usual leak- 55 age attendant on such devices when the parts x are made separately and united by joints.

J is a condenser, which may or may not be employed.

In Fig. 5 is represented another variation, 60 in which the automatic valve is located entirely within the oil-exit passage, and is opened by back pressure when steam is turned into the dry-pipe and closed by direct pressure from within the lubricator when steam is 65 turned off. K is a valve, with a cylindrical

portion, k, and with wings k'. When steam is turned on the back pressure forces the valve down until the part k passes the openings k'. The oil will then flow up through the channels formed between the ribs, and when steam is 70 shut off the direct pressure from the lubri- 70 cator forces the valve up and closes the flow of oil.

The valve-chamber G² is preferably made in a single piece, as shown in Fig. 3, since in 75 this form it serves at the same time to secure the glass tube C in its place, and the latter can be removed or a new one inserted by remov- 80 ing the part G², after which the tube can be slipped up through from beneath. It serves 85 at the same time as a funnel to give direction to the visible drop of oil.

What we claim is—

1. In combination with the oil-exit passage 85 of a lubricator, a valve located therein to close the passage, said valve constructed to open by the back pressure of steam through the oil-exit pipe when steam is turned on and close by the pressure of steam in an opposite direction through another steam-passage when 90 steam is shut off, substantially as and for the purposes described.

2. In combination with the oil-exit passage 95 of a lubricator, a valve connected with a plun- ger located in an independent steam-cham- 100 ber, the construction being such that when steam is turned on the back pressure through the oil-exit passage will open the valve, but when steam is turned off the steam acting upon the plunger in the independent chamber 105 will close the valve, substantially as and for the purposes described.

3. In combination with the oil-exit passage 105 of a lubricator, a valve connected with and forming a part of a plunger, which projects 110 into an independent steam-chamber, the con- struction being such that the back pressure of steam through the oil-passage when steam is turned on will open the valve, and when steam is turned off the resisting pressure on the 115 plunger in the steam-chamber will close the valve, substantially as described, and for the purposes set forth.

4. In combination with the oil-exit passage 115 of a lubricator, a valve located therein, a 120 valve-actuating plunger located in an inde- 125 pendent steam-chamber, and a steam-passage leading from the boiler to the steam-chamber below the latter, whereby accumulation of wa- 130 ter in the plunger-chamber is avoided, sub- stantially as described.

5. In combination with the oil-exit pipe of 125 a lubricator, an automatic valve located there- in, said valve adapted to open and remain open when steam is turned on, and to close 130 and remain closed when steam is turned off, substantially as and for the purposes described.

6. In combination with the oil-exit passage 130 of a lubricator, an automatically-operating valve located therein between the oil-reser-

voir and the visible feed or transparent chamber, substantially as and for the purpose described.

7. In a lubricator, the combination, with the oil-exit passage, of an automatic valve located therein and made to open by the back pressure of steam through the oil-passage when steam is on, and close by external pressure in an opposite direction upon the valve when steam is shut off, substantially as described.

8. The part G², formed in a single piece and

acting as a valve-chamber, as a fastening to secure the glass tube in its place, and as a funnel for giving direction to the visible drops of oil.

In testimony whereof we sign this specification in the presence of two witnesses.

HENRY C. HODGES.
